RECORDING AND REPRODUCING OF SOUND

August Karolus, Zollikon/Zurich, and Erna Hamburger and André Henry, Yverdon, Switzerland, assignors to Paillard S. A., a corporation of Switzerland

Application July 7, 1948, Serial No. 37,356
In Switzerland July 10, 1947

18 Claims. (Cl. 179—100.3)

1

The present invention relates to sound records and improved apparatus and processes for the recording and reproducing of sound.

In the sound film art, the sound phenomena are recorded as phonograms on a carrier strip which unreels at a constant rate of speed. The sounds or sound phenomena, of whatever kind, are generally recorded upon the strip in the form of slit images which follow one another in the direction of motion of the strip.

Depending on whether the length of the image or its degree of transparency is the variable factor, a distinction is made between

(a) The variable area or fixed density process, and

(b) The variable density process.

Generally speaking, and regardless of what process is used, the higher the quality required of the sound record, the more difficult it is to carry out the photographic process as a whole.

As a matter of fact, it is well known that the non-linear distortions which cause the appearance of harmonics, the formation of sounds through interference, and undesirable detection effects, are due chiefly to the fact that the characteristic of photographic reproductions is not linear.

The problems of eliminating distortions and of high fidelity reproduction of the sound volume are extremely difficult to solve with the known processes, the more so since a better volume range in the reproduction, i. e., an increased range for the intensity variations of the reproduced sound, entails still greater distortions.

Various methods aiming at obtaining higher sound fidelity have made it possible to extend the sound volume range to a certain extent while keeping distortions and background noises at an acceptable level. But these methods have not proved satisfactory for the perfect reproduction of music, for instance.

The process hereinafter described represents a considerable improvement in the recording of sound on strips used either for direct reproduction, or for printing on film, or for reproduction on paper. To obviate the aforementioned difficulties, the instantaneous value of the amplitude of the sound wave is represented by the respective position of the images of a slit which follow one another at intervals of time shorter than the duration of half a cycle of the highest sound to be recorded and not, as heretofore, by their length or transparency. Thus, in reproducing the record, the impulses representing the sound wave to be reproduced are identified solely

2

by their respective positions, so that neither their degree of opacity nor the non-linearity of the characteristic of photographic reproduction plays any part in the process.

5 It will thus be understood that, in the present invention, any variation in the opacity of the slit images has no bearing on the reproduced sound phenomenon. Amplitude limitation renders the process absolutely independent of fortuitous variations in the opacity of the images that may occur during recording or printing, and of variations in the intensity of the light that may occur during reproduction.

However, when frequency modulation is used, 15 it is desirable to provide a carrier wave whose frequency is much higher than the highest audible frequency to be recorded. Therefore, in the usual type of recording where the images succeed one another in the direction of motion of the strip, the unreeling speed of the strip and the diameter of the reels are such as to render manipulation extremely difficult and the consumption of material prohibitive. In the process hereinafter described it is proposed to avoid these drawbacks by using a known process, 20 namely, transverse scanning, in which a series of images arranged in rows approximately perpendicular to the direction of motion of the strip, are recorded on the latter. The scanning speed corresponds then to the recording speed and the unreeling speed of the film is substantially reduced.

The present invention has for one of its objects the provision of devices for recording and 35 reproducing sound phenomena, in which a rectilinearly and uniformly moving carrier strip receives an image, and is scanned, respectively, by means of a beam of light passing through a slit. These devices differ from the known ones in that the light beam is optically controlled in rhythm with a frequency-modulated carrier wave, the instantaneous frequency of the carrier wave being characterized by the instantaneous 40 value of the sound wave, the beam thus modulated being periodically deflected, preferably perpendicularly, relative to the direction of travel of the strip, so that the latter receives an image, or is scanned, respectively, in accordance 45 with trajectories that follow one another.

The recording device comprises on the one hand, a known device for electrically transforming the sound phenomena into a frequency-modulated carrier wave and, on the other hand, a device for the optical modulation of a light beam

55

by this frequency-modulated wave. Still another device is provided for photographically recording upon the strip, this being achieved by optical deviation of the light beam, preferably perpendicularly relative to the direction of motion of the strip.

The carrier strip for recording sound phenomena obtained in accordance with the aforementioned device, is characterized by the fact that the strip carries a succession of slit images of the same dimensions and the same opacity and which, in the non-modulated state, follow one another at equal distances corresponding to the mean frequency of the carrier wave and which are influenced by the sound phenomena in such a way that their instantaneous frequency corresponds to the instantaneous value of the sound wave, and by the fact that the rows of successive slit images form an angle, in other words, are arranged preferably transversely relative to the direction of motion of the strip.

Preferred ways of carrying out the invention will now be described by way of example with reference to the accompanying diagrammatic drawings in which

Figure 1 is a plan of recording apparatus in which frequency modulation is employed,

Figure 2 is a plan of reproducing apparatus for reproducing sounds from the records produced with the apparatus of Figure 1,

Figure 3 is a plan of scanning apparatus,

Figure 4 is a section on the line IV—IV of Figure 3, and

Figure 5 illustrates a portion of another form of reproducing apparatus.

Referring to Figure 1, the recording apparatus here illustrated comprises an electrical audio-frequency generator S such as a microphone for example, feeding a low frequency amplifier ABF controlling a frequency modulator M, a light modulator ML controlled by the frequency-modulated tension issuing from a power amplifier AP, an optical system O and a scanning device B serving to record upon a film F a series of images of a slit which succeed one another in rhythm with the frequency-modulated tension.

The modulation of the light may be achieved with the aid of either gas discharge lamp, such as, a high pressure mercury lamp or Kerr cell or a supersonic valve functioning on the Debye-Sears effect. See U. S. Patent No. 2,084,201. These devices permit strong light intensities to be modulated with good output up to 100 kcs.

In order that the images on the film may be well-contrasted, the signals may be transformed, with the aid of any known or suitable device, into signals of rectangular wave-form.

The reproducing apparatus illustrated in Figure 2 comprises a source of light O' of constant intensity, a scanning device B' with which a beam of light from the source O' is swept periodically and transversely across the film record F and a photo-electric cell 13 which collects light passing through the record.

Current originating on the anode of the cell and which is in the form of impulses succeeding one another in the rhythm of the modulated frequency, is amplified by an amplifier A. The voltage thus obtained traverses in succession an amplitude limiter LA, a discriminator D and a detector DE. The detected current, after amplification in a low frequency amplifier BF is finally used to energise a loud-speaker HP.

The alternative form of sound head illustrated in Figure 5, comprises a combined photo-elec-

tric cell and electron multiplier 13', with the aid of which electrons emitted from a photo-electric substance are multiplied, thereby enabling one or more of the amplifying stages represented by A to be dispensed with, and diminishing ground noise.

The reproducing apparatus described above, is intended for reproduction by transmission of light through a film, as distinct from reproduction by reflection, and is suitable for use with records on ordinary transparent film or with records printed on strips of cellophane. But the record may be transferred to a strip of paper by impression or photographic copying. Such records on opaque films are explored by means of reflected light, with the aid of any of the known devices in everyday use in television. In such a case, the scanning device hereinafter described for reproduction by transparency, needs to be modified only in details of construction in order to render it suitable for use with opaque records.

Figures 3 and 4 illustrate scanning apparatus with which the film can be scanned transversely, that is to say, substantially perpendicularly to its direction of motion.

This scanning device comprises a platform 9 rotatably mounted on an axis 21 and rotated by an electric motor (not shown). The plane of rotation of the platform 9 is parallel to the plane of the film F which runs between two sprockets 12 having teeth 19 engaging perforations 20 in the film to draw it along at constant speed.

The platform 9 carries a plurality of equiangularly spaced lenses 10 the optic axes of which are all parallel to the axes of rotation 21.

Also fixed on the platform 9 are a plurality of mirrors 11 one of which faces, and cooperates with, each lens 10. Each mirror is inclined at 45° to the plane of the platform and the normal to the centre of each mirror intersects the axis 21.

The several mirrors 11 thus substantially envelop the surface of a frustum of a cone and within this frustum is located, separate from the platform 9, a fixed source of light 7 within a housing 22 formed with an aperture 23 opposite which is located a condenser lens 8 concentrating the light issuing from the source 7 through the aperture 23, upon a slit 6 located precisely on the axis 21.

This scanning device functions in the following way:

Light rays emanating from the source 7 and passing through the aperture 23 are concentrated by the condenser 8 upon the slit 6 so as to form a conical beam of solid angle α measured perpendicularly to the axis of rotation 21.

When the film F is set in motion at a constant speed in the direction of the arrow 2 and the platform 9 is rotated at a constant speed, the beam of rays passing through the slit 6 falls in turn upon each of the mirrors 11, each of which reflects the beam along the optic axis of lens 10 cooperating with it. This lens 10 concentrates the light as a beam 3 onto the film F. Since the optical element constituted by a mirror 11 and a lens 10 is moving at a constant speed, and the mirror 11 intercepts only that part of the beam which traverses the slit 6, it will be appreciated that the beam of rays 3 issuing from the lens 10, moves with the two-part optical element constituted by a mirror 11 and a lens 10.

The beam of light 3 describes an arc of a circle the angular length of which corresponds approx-

imately with the angle α of the beam of rays emerging from the slit 6 and thus scans the film F perpendicularly to its direction of its movement, whilst the optical element, i. e. the mirror 11 and lens 10, project upon the film F a scanning spot which is an image of the slit 6.

As a result of the uniform rectilinear movement of the film and the transverse scanning of the beam, the images produced on the film move over it along an arc the chord of which is 10 obliquely inclined with respect to the longitudinal axis of the film. Usually the chord very nearly coincides with the transverse direction.

As the platform 9 rotates at constant speed, the elements 10, 11 in turn enter the beam emerging from the slit 6, and each element projects upon the film a fresh row of images of the slit 6. The angle α of this beam corresponds to the angle separating two neighbouring mirrors 11, so that one mirror enters the beam of rays emerging from the slit 6 as the preceding mirror leaves it.

It follows that during a short space of time, corresponding with that taken by the platform 9 to pass through the angular length of a mirror, two optical elements 10, 11, project an image simultaneously upon the film.

Thus there is a kind of overlapping when the first few images of one row are being recorded (or reproduced) simultaneously with the last few images of the next preceding row, and these two groups of images may be said to be isochronal. The optical system as a whole is so designed that, during reproduction, the sum of the light falling on two elements simultaneously is constant and at all times equal to the whole of the light falling on one element working singly. Discontinuities are thus avoided.

The above described process of recording possesses several advantages. In the first place, if one assumes, by way of example, that the film has a width of 7.5 cm. and that the recording speed is 4.5 m./sec., it may be easily calculated that the film must be scanned 60 times per second. If now the image of the slit 6 on the film has a height of 1 mm., the minimum speed of motion of the film in order to avoid an overlapping of the rows of images is 6 cm./sec.

This speed is small in comparison with the speeds hitherto considered necessary for longitudinal recording. Consequently, the present process facilitates editing, for example the finding of a passage, since the length to be unwound is shorter. In order still further to facilitate such a search figures, perforations or marks can be provided on the edge of the film. The marks may be placed on the film by luminous impression, or by mechanical or manual impression and may be effected entirely automatically.

If one assumes a recording speed of 4.5 m./sec. and an image width of 0.03 mm., frequencies up to 70 kcs. can be recorded. Frequency modulation must then be effected on a carrier-wave the frequency of which must be selected to be as low as possible, since the scanning speed and film consumption are proportional thereto. In order that the frequency modulation may produce the best results with respect to the ground noise level, it is necessary that the frequency deviation shall be at least twice as great as the highest audible frequency to be recorded. If, for example, a low frequency high limit of 7 kcs. is chosen, then a carrier-wave of 50 kcs. and a variation of ± 15 kcs. are used. The number of images of the slit

per cm. of recording then varies, in accordance with the audible frequency, between

$$\frac{35,000}{450} = 78 \text{ images/cm.}$$

5 and

$$\frac{65,000}{450} = 144 \text{ images/cm.}$$

i.e. around a mean value of

$$\frac{50,000}{450} = 111 \text{ images/cm.}$$

In addition to changing position with reference to the normal equidistant positions, the images may also vary in size, the images remote from one another being larger than neighbouring ones. This is the case, for example, when frequency modulation is employed, but is only a secondary effect which does not occur when, for example, modulation by impulse is employed.

The values and figures indicated above are given only by way of example in order that the best form of the invention known may be understood. When using optical systems of high quality and employing ultra-violet rays, for example, for the recording, it is possible to obtain much finer images, so that a speed of movement of 4.5 m./sec., indicated above, must not be considered as the minimum limit of the recording speed. Furthermore recordings of a much more extensive range of sound waves and utilising a much greater frequency variation may be achieved.

A device for transverse scanning has been described herein by way of example, but it will be appreciated that any other television scanning devices, for example a mirror drum, may be adapted for transverse recording and exploration of a film F. The source of light and the whole 30 of the scanning device may also be replaced by, or consist of, a cathode ray tube. Such a device provides a very simple way of scanning the film transversely; for the ray may be deflected linearly at the desired rate and may be simultaneously electrically modulated.

When films are employed certain difficulties may arise from their shrinking. These difficulties may however be easily obviated by providing a device with which the radial position of the lens 50 10 may be adjusted. In fact, by modifying the radial position of the optical elements 10, 11, the curve of the arcs traversed by the exploring beam may be varied and thus made to conform to the curve of the arcs on the film after shrinking.

55 In the case where the scanning device comprises a mirror drum, shrinkage may be compensated for by slightly altering the distance separating the drum from the film.

We claim:

60 1. A device for recording sound data comprising a rotatable member having a plurality of circumferentially spaced lenses, a stationary diaphragm aligned with the axis of rotation of said member, said diaphragm having a slit aperture therethrough, a stationary light source on one side of said slit, means for directing light passing through said slit successively through said lenses as said rotatable member rotates, a photosensitive strip for receiving light passing through said lenses, and means for supporting and moving said film radially relative to said rotatable member.

65 2. A device as defined by claim 1 in which the lenses are so spaced relative to the light passing through the slit that when the axis of the light beam bisects the central angle of a pair of con-

secutive lenses, some of the light therefrom will pass through both of the lenses to form isochronal images of the slit on either side of the strip.

3. A device as defined by claim 1 having means for radially adjusting the position of lenses on the rotatable member.

4. A device for reproducing sound from a strip containing sound data comprising a rotatable member having a plurality of circumferentially spaced lenses, a stationary diaphragm aligned with the axis of rotation of said member, said diaphragm having an aperture therethrough, a stationary light source on one side of said diaphragm, means for directing light passing through said aperture successively through said lenses as said rotatable member rotates, means for supporting and moving said strip radially relative to said rotatable member to receive light passing through said lenses, photoelectric means for receiving light from said strip and means for converting electrical impulses generated in said photoelectric cell into sound.

5. A device as defined by claim 4 in which the photoelectric cell is of the type which emits electrons and in which the emitted electrons are multiplied by secondary emission.

6. The combination as defined by claim 4 having means for radially adjusting the position of the lenses on the rotatable member.

7. In a device for recording sound phenomena, the combination of means for moving rectilinearly and uniformly a photosensitive carrier strip, means for scanning said strip substantially transversely of its direction of motion with a beam of light, a light modulating device, means for controlling said beam by said modulating device, means for producing an electrical carrier wave to excite said modulating device, means sensitive to the sound phenomena to be recorded for modulating the frequency of said carrier wave, whereby the photosensitive strip will record lines containing each a multiplicity of rectilinear slit images of substantially uniform height and opacity and the distance between two successive slit images in a line on the strip in the direction of scanning will be a function of the instantaneous intensity of the sound phenomena.

8. In a device for recording sound phenomena as defined by claim 7, the axis of the scanning means being perpendicular to the plane of the photosensitive carrier strip.

9. In a device for recording sound phenomena as defined by claim 7, the axis of the scanning means being parallel to the plane of the photo-sensitive carrier strip.

10. In a device for recording sound phenomena, the combination of means for moving rectilinearly and uniformly a photosensitive carrier strip, means for scanning said strip substantially transversely of its direction of motion with a beam of light, a light modulating device, means for controlling said beam by said modulating device, means for producing an electrical carrier wave to excite said modulating device, means sensitive to the sound phenomena to be recorded for pulse modulating said carrier wave, whereby the photo-sensitive strip will record lines containing each a multiplicity of rectilinear slit images of substantially uniform height and opacity and the distance between two successive slit images on the line in the strip in the direction of scanning will be a function of the instantaneous intensity of the sound phenomena.

11. In a device for recording sound phenomena,

the combination of a rotatable member having a plurality of circumferentially spaced lenses, a stationary diaphragm having a slit aperture therethrough, a stationary light source on one

5 side of said slit, means for directing light passing through said slit successively through said lens as said rotatable member rotates, means for supporting and rectilinearly moving a photosensitive carrier strip radial to said rotatable member 10 in the path of light passing through said lenses, a light modulating device, means for controlling said beam by said modulating device, means for generating an electrical carrier wave to excite said modulating device, and means sensitive to 15 the sound phenomena to be recorded for modulating the frequency of said carrier wave, whereby the photosensitive strip will record lines containing each a multiplicity of slit images of substantially uniform height and opacity and the distance 20 between two images in a line on the strip in the direction transverse of the strip will be a function of the instantaneous intensity of the sound phenomena.

12. The combination as defined by claim 11 25 in which the lenses are so spaced relative to the light passing through the slit that when the axis of the light beam bisects the central angle of a pair of consecutive lenses some of the light therefrom will pass through both lenses to form 30 isochronal images of the slit on either side of the strip.

13. In a device for reproducing sound phenomena from a transparent strip containing sound data in the form of transverse lines of substantially parallel and rectangular opaque bars spaced from each other, said bars being of substantially uniform height and opacity and their spacing being a function of the instantaneous frequency of the sound to be reproduced, comprising a rotatable member having a plurality of circumferentially spaced lenses, a stationary diaphragm aligned with the axis of rotation of said member, said diaphragm having an aperture therethrough, a stationary light source on one side of said diaphragm, means for directing light passing through said aperture successively through said lenses as said rotatable member rotates, means for supporting and moving said strip radially relative to said rotatable member to receive light passing through said lenses, photoelectric means for receiving light passing through said transparent strip, means for amplifying amplitude-limiting, discriminating and detecting electrical impulses generated in said photoelectric means into an audio frequency signal, and means for transforming said audio frequency signal into sound.

14. A device as defined by claim 13 in which the photoelectric means is of the type which emits electrons and in which the emitted electrons are multiplied by secondary emission.

15. In a device as defined by claim 13, means for radially adjusting the position of the lenses on the rotatable member.

16. In a device for reproducing sound phenomena from a light reflecting strip containing sound data in the form of transverse lines of substantially parallel and rectangular bars spaced from each other, said bars being of substantially uniform height and their spacing being a function of the instantaneous frequency of the sound to be reproduced, comprising a rotatable member having a plurality of circumferentially spaced lenses, a stationary diaphragm aligned with the axis of rotation of said member, said diaphragm

having an aperture therethrough, a stationary light source on one side of said diaphragm, means for directing light passing through said aperture successively through said lenses as said rotatable member rotates, means for supporting and moving the said strip radially relative to said rotatable member to receive light passing through said lenses, photoelectric means for receiving light reflected from said strip, means for amplifying, amplitude-limiting, discriminating and detecting impulses generated in said photoelectric means into an audio frequency signal, and means for transforming said audio frequency signal into sound.

17. A device as defined by claim 16 in which the photoelectric means is of the type which emits electrons and in which the emitted electrons are multiplied by secondary emission.

18. In a device as defined by claim 16, means for radially adjusting the position of the lenses on the rotatable member.
